Add. 10.

UNITED STATES PATENT OFFICE

GEORGE W. WATTS, OF WHITING, INDIANA, ASSIGNOR TO STANDARD OIL COMPANY,
OF WHITING, INDIANA, A CORPORATION OF INDIANA

HEAT-EXCHANGE APPARATUS

Application filed July 27, 1925. Serial No. 46,304.

The present invention relates to improvements in heat exchange apparatus and more particularly to methods and apparatus for preventing such devices from becoming gas bound. In heat exchange devices for use in the oil industry it is desirable to utilize the heat of the constituents driven off from the still to preheat the crude or fresh stock to be distilled. The fresh stock then acts as a liquid cooling medium. This has a tendency to cause a slight distillation of the fresh stock with a corresponding increased tendency for the space surrounding the tubes in the heat interchanger to become gas bound. It is the object of my invention to provide means whereby this gas is removed without any contamination of the refined constituents with the unrefined fresh stock. This will be fully understood from the following description, in which apparatus for carrying the invention into effect, is shown somewhat diagrammatically and in section.

Referring more particularly to the drawings, the numeral 5 designates the upper portion of a fractionating column or other like device, which is surmounted by a heat exchange device 6, serving in the present instance as a reflux condenser. In the form illustrated, this device is provided internally with the spaced tube plates 7 and 8, between which extend the tubes 9 serving for the passage of vapors through the device.

A suitable cooling medium is introduced in controlled quantities through the pipe 10 into the space between the tube plates 7 and 8 and surrounding the tubes 9. The cooling medium makes its exit through the pipe 11.

For the proper operation of a heat exchange device of the type herein set forth, it is necessary that the space between the tube plates and surrounding the tubes 9 be completely surrounded by the cooling medium, which is ordinarily a liquid such as water, oil, a condensable gas or the like, but may be gas (i. e. with air in it). In the operation of such devices, it frequently occurs that, in the flow of the cooling medium through the inlet pipe to the exit pipe therefor, a certain portion of the space between the tube plates 7 and 8 becomes charged with gases or vapors forced

out of the cooling medium by the heat applied thereto or with incondensable gas, such as air, when the cooling medium is a condensable gas, and these gases or vapors collect in a remote part of the space, preventing access of the cooling medium thereto. In the form illustrated in the drawing, this gas bound space is shown and is designated by the numeral 12.

In accordance with this invention, the cooling medium passing out of the heat exchange device through the exit pipe 11 passes through the throat of a Venturi tube 13 and thence into the discharge line 14. The Venturi tube 13 is surrounded by a suitable casing 15 and openings 16 are provided from this casing to the interior of the throat of the Venturi tube. A valved tube 17 connects that portion of the space in the heat exchange device occupied by the cooling medium in which gas tends to collect with the interior of the chamber 15. The passage of the cooling medium discharged through the exit pipe 11 through the throat of the venturi causes suction to be exerted through the chamber 15 and the connection 17 with the gas bound portion of the heat exchange device, and thereby withdraws the collected gas and permits the entire space between the tube plates and surrounding the tubes to be occupied by the cooling medium and it likewise improves the circulation of the cooling medium through the device. The tube 17 is valved so that, after removal of the gas or vapor causing "gas binding", the flow of the cooling medium therethrough may be prevented.

Although the present invention has been described in connection with the specific details of apparatus suitable for carrying it into effect, it is not intended that these details shall be regarded as limitations upon the scope of the invention, excepting so far as included in the accompanying claims.

I claim:

1. In a heat exchange device having a space occupied by a heat transfer medium, means for supplying a heat transfer medium to said space, exit means through which said heat transfer medium is caused to flow after leaving said space, means for causing the exit flow of the heat transfer medium to produce a

pressure depression, and means for utilizing said pressure depression to remove collected gas from the space occupied by the heat transfer medium.

- 5 2. In a heat exchange device having a space occupied by a heat transfer medium, means for causing the heat transfer medium to flow into said space, an exit pipe for the discharge of the heat transfer medium from said space,
10 a Venturi tube through which the discharged heat transfer medium passes, and means for connecting a portion of said space in the heat transfer device in which gas tends to collect with the throat of said venturi, thereby without
15 drawing gas from said portion of the space.

GEORGE W. WATTS.
